TEA KETTLE

Lurelle Guild, Darien, Conn., and Roger E. French, New Kensington, Pa., assignors to Aluminum Company of America, Pittsburgh, Pa., a corporation of Pennsylvania

Application June 6, 1955, Serial No. 36,377

Term of patent 14 years

(Cl. D44—25)

Fig. 1 is a top plan view of a tea kettle embodying our new design;

Fig. 2 is an elevational view of the same;

Fig. 3 is an elevational view at 90° from the view of Fig. 2;

Fig. 4 is a cross sectional view through the handle taken on the line IV—IV of Fig. 2; and

Fig. 5 is a cross sectional view through the handle taken on the line V—V of Fig. 2.

We claim:

The ornamental design for a tea kettle, substantially as shown.
